UNITED STATES PATENT OFFICE.

JOB C. HUGULEY AND CARL M. HUGULEY, OF SAN DIEGO, CALIFORNIA.

MOP MACHINE.

Application filed September 18, 1924. Serial No. 738,384.

Our invention relates to a machine for making or assembling mops and mop heads, and the objects of our invention are: first, to provide such a machine for cutting yarn to certain lengths and clamping the same within a clamp member, thus forming a mop or a mop head; second, to provide a machine of this class whereby the yarn is packed at one portion intermediate its ends to substantially the shape desired, and which is provided with a yarn clamp member receiving vise consisting essentially of a pair of relatively contractible jaws adapted to contract or form the clamp member around the packed portion of the yarn; third, to provide a machine of this class for simultaneously packing yarn or other similar material intermediate its ends and clamping the same in the clamp member; fourth, to provide a machine of this class whereby the initial yarn packing operation must precede the clamping operation, the former operation setting the machine in a position or condition to perform the latter; fifth, to provide a mop head assembling machine whereby the yarn for the mop head is packed by means of a foot operated lever and whereby the yarn is clamped in a clamp member by a slight movement of a hand operated lever of relatively great leverage; sixth, to provide such a machine whereby the shifting of a foot operated packing means to substantially its extreme position sets the machine in a certain position, by reason of a shifted cam means, as to permit the yarn clamp member to be contracted by a slight movement of a hand operated lever; seventh, to provide as a whole a novelly constructed and operated mop and mop head making and assembling machine, and eighth, to provide such a machine which is very simple and economical of construction, durable, efficient, easy to operate, and which will not readily deteriorate or get out of order.

With these and other objects in view, as will appear hereinafter, our invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a front elevational view of our mop head assembling machine, showing cer-

tain portions thereof fragmentarily and the means for holding the yarn broken away; Fig. 2 is a side elevational view thereof, showing by dotted lines the members of the packing means in a certain shifted position; Fig. 3 is an enlarged sectional elevational view of the yarn clamp member contracting means with the section taken through 3—3 of Fig. 6; Fig. 4 is a top view of the means shown in Fig. 3; Fig. 5 is a transverse sectional view thereof, taken through 5—5 of Fig. 3; Fig. 6 is a perspective view of the yarn clamp member in an unfolded position preparatory to receiving the yarn, and Fig. 7 is a fragmentary side elevational view of the yarn cutting means shiftably mounted on the longitudinal guide and supporting rods thereof.

Like characters of reference refer to similar parts and portions throughout the several views of the drawings.

The frame 1, supporting plate 2, guide and supporting rods 3, brackets 4; adjustable stop member 5, adjustable cutting member supporting bracket 6, cutting member 7, plate 8, housing members 9 and 10, screws 11, pivot members 12, yarn clamp member contracting arms 13 and 14, pins 15, rack member 16, spring 17, shoe 18, screw 19, rack shifting members 20, pin 21, packing plates 22, pins 23, bolts 24, packing arm 25, shaft 26, brackets 27, connecting rod 28, foot lever 29, foot lever supporting bracket 30, guide members 31, spring 32, roller 33, cam 34, shaft 35, brackets 36, hand lever 37 and the weight 38, constitute the principal parts and portions of our mop machine.

Our machine consists essentially of an adjustable means for measuring yarn, a means for cutting the yarn to certain lengths, a means for packing the yarn intermediate its ends, and a means for contracting or forming a clamp member around the packed portion of the yarn. Said means are supported on a frame 1 which is provided at its upper portion with a supporting plate 2. Through the upper portion of said frame and underneath the supporting plate 2 extend a pair of spaced apart, parallel guide and supporting rods 3, which are secured in position to the frame 1 and plate 2 by means of brackets 4, said rods extending laterally to either side of the frame. On the rods 3 extending to one side of the frame is shiftably mounted a stop member 5 which is adapted

to be clamped to one of said rods by means of a split portion on the member 5 and a bolt 5^a extending through said split portion. On the other side of the machine and also mounted on the rods 3 is a guide and cutting member supporting bracket 6, which is adapted to be clamped on one of the rods 3 by means of a bolt 6^a, substantially as shown in Fig. 7 of the drawings. The bracket 6 is preferably bifurcated at its upper end and provided at one of the bifurcated portions with a guide portion 6^b and at the other bifurcated portion with a guide means provided with a transverse slot 6^c in which is reciprocally mounted a cutting member 7, the cutting portion of which extends below the longitudinal, curved guide slot therein.

At the front portion of the supporting plate 2 is secured another supporting plate 8 by means of bolts 8^a, said plate being provided with a rectangular channel 8^b extending from front to rear. At the front and rear portions of said channel are positioned the lower ends of the housings 9 and 10, which are spaced from each other. Within and at the lower ends of said housings are positioned the pivot blocks 12 which are secured in position against the lower sides of the housings by means of screws 11 extending into said blocks from the lower side of the plate 8, thus also securing the housings in position against said plate. At the upper sides of the pivot blocks 12 are provided lugs 12^a on which are pivotally mounted, by means of pins 15, the lower bifurcated ends of the clamp member contracting arms 13 and 14, which, when separated or in an open position, are enclosed at the sides by the housings 9 and 10, respectively. Said arms 13 and 14 are provided at their lower bifurcated portions with gear portions 13^a and 14^a, respectively, which extend toward each other and engage with the teeth of the vertically reciprocable rack member 16 which is shiftably mounted between the pivot blocks 12 and the upwardly extending portions of the plate 8 forming the channel 8^b therein. At the lower end of the rack member is provided a recess 16^a in which is positioned the one end of a compression spring 17, which engages at its other end the top side of the supporting plate 2, as shown best in Figs. 3 and 5 of the drawings. Within a slot 16^b at the upper end of the rack member 16 is secured the shoe 18 by means of a screw 19, which shoe extends into the bifurcated portions of the arms 13 and 14, as shown best in Figs. 3 and 4.

The upper side of the shoe 18 is formed or shaped substantially the same as the band portion C¹ of the yarn clamp member or ferrule C, shown in perspective in Fig. 6 of the drawings. The partially cylindrical portions C² of the clamp member or ferrule C are adapted to fit into curved slots 13^b and

14^b near the outer ends of the arms 13 and 14, respectively. When the clamp member or ferrule C is in an open position, as shown by solid lines in Fig. 3, the clamp member C rests at substantially three points only, namely, at the outer ends of the partially cylindrically shaped portions C² and at the lower band portion C¹. The whole of the adjacent sides of the contracting arms 13 and 14 are shaped substantially to conform with the exterior surface of the clamp member C when the same is contracted around the yarn, as shown by dotted lines in Fig. 3 of the drawings, the shape of the arms forming the clamp member to the last mentioned shape.

At the sides of the rack member 16 are pivotally mounted, by means of a pin 21, the rack shifting members 20, which are adapted to shift the rack member 16 downwardly when engaged by the lower edges of the outer ends of the packing members 22 which are adjustably secured at their opposite ends by means of pins 23 and bolts 24 to the end of the packing arm 25. Said arm 25 is rotatably mounted on a shaft 26 which is supported on spaced apart brackets 27 mounted on the rear portion of the supporting plate 2. The packing members 22 are spaced apart the same distance as the width of the housings 9 and 10. At the sides of the packing members 22 adapted to engage the rack shifting members 20 are provided cutaway portions 22^a, the sides of which are inclined with each other and serve to pack the yarn inwardly as well as downwardly within the clamp member C. Thus, it will be seen that the yarn is packed substantially on all sides when the packing members 22 are forced downwardly against the yarn.

On the inner sides of the packing members 22 are provided inwardly extended, spaced apart portions or lugs 22^b and 22^c, which serve as guides for permitting the partially cylindrical portions of the clamp member C to be shifted to a vertical position when being contracted when the partially cylindrical portions C² of the clamp members leave the housings, as shown best in Fig. 3. It will be here noted that the one partially cylindrical portion of the clamp member C extends over the other when in a contracted position; therefore, the one portion is adapted to be made larger than the other. By reason of one of said partially cylindrical portions C² being smaller, the side walls of the housing 9 are slightly contracted, as shown best in Fig. 4, and, therefore, the lugs 22^b of the packing members 22 extend inwardly a greater distance than the lug 22^c, so that the inner sides or guide portions of the housings come flush with the lugs 22^b.

At the lower side of the end of the arm

25 is provided a bifurcated lug to which is pivotally connected the one end of the connecting rod 28 which is pivotally connected at its opposite end intermediate the ends of 5 the foot lever 29. Said foot lever is pivotally supported at one end in a bracket 30 and guided intermediate its ends by guide brackets 31. Said foot lever is adapted to be held in an upward position by a tension 10 spring 32 secured at one end thereto and at its opposite end to the frame.

The arm 25 is also provided with a downwardly extending arm 25^a, which extends through the supporting plate 2 and is provided at its end with a bifurcated portion 25^b in which is revolvably mounted a roller 33. When the foot lever 29 is shifted downwardly so that the packing members 22 engage the rack shifting members 20, the 15 roller 33 assumes the position shown by dotted lines in Fig. 2 of the drawings. When the roller is in the latter position stated, the same is adapted to be engaged by the end of a cam member 34 which is secured to a 20 shaft 35 revolvably mounted in downwardly extending brackets 36 below the supporting plate 2. On the one end of the shaft 35 is secured the hand lever 37 of considerable 25 length, which is provided at the end opposite the handle portion with a weight 38, the lever 37 being preferably offset intermediate its ends to clear the guide and supporting rods 3. When the hand lever 37 is forced downwardly, the cam 34 engages the roller 33 when the latter is in the dotted line position, thus forcing the arm 25 and the packing members 22 about their pivotal mounting against the rack shifting members 20 which force the rack member downwardly 30 and mutually shift the clamp member contracting arms 13 and 14 towards each other, thus clamping the yarn in position in the clamp member or ferrule C.

In order to make a mop or mop head, a 45 clamp member or ferrule C is positioned on the shoe 18 between the arms 13 and 14; the cutting member 7 is then raised and the end of the yarn previously cut is drawn through the guide portion of the bracket 6, through 50 the space between the housings 9 and 10 and against the stop member 5. This gives the desired length of the yarn, the members 5 and 6 having previously been adjusted to the desired position. The cutting member 55 7 is then forced through the yarn; or the yarn may be cut after the same is assembled with the clamp member. The vise, consisting of the arms 13 and 14 and their supports, is positioned centrally between the 60 stop member 5 and the cutting member 7. The foot lever is then depressed, compressing the yarn at its middle portion. The hand lever 37 is then shifted downwardly 65 and the clamp member C or ferrule is clamped around the packed portion of the

yarn. The completed mop or mop head, preparatory to being secured to a handle, is then removed from the machine and another clamp member or ferrule inserted therein and the above described operation repeated. 70

The shoe 18, against which the curved band portion of the yarn clamp member rests, may be easily replaced for shoes of greater or less length so that mop heads of different sizes may be made with the same 75 machine by merely replacing the shoe, the difference between mop heads having the same size handle being merely in the length of the curved band C¹ of the clamp member or ferrule. 80

When desiring to use clamp members or ferrules having partially cylindrical portions of greater diameter, the whole vise means, including the housings, the mutually contractible jaws and the corresponding co-acting members, are replaced for correspondingly larger ones. The same packing means, however, is used by merely unscrewing the bolts 24 and shifting the packing members 22 outwardly and inserting shims 90 between said members and the arm 25, and then retightening the bolts 24. 95

It is obvious from this construction, as illustrated in the drawings and disclosed in the foregoing specification, that there is provided a machine as aimed at and set forth in the objects of the invention, and though we have shown and described a particular construction, combination and arrangement of parts and portions, we do not wish to be limited to this particular construction, combination and arrangement, but desire to include in the scope of our invention the construction, combination and arrangement substantially as set forth in the appended 100 claims. 105

Having thus described our invention, what we claim as new and desire to secure by Letters Patent is:

1. In a machine of the class described, a 110 measuring means, a cutting means in connection with said measuring means for cutting material to certain lengths, a packing means positioned intermediate the limits of said measuring means for packing said material, and a clamp member contracting means in connection with said packing means adapted to receive a clamp member and contract the handle receiving portions thereof relatively to each other and clamp 120 the clamp member about said material at its packed portion. 115

2. In a machine of the class described, a 125 measuring means, a cutting means in connection with said measuring means for cutting material to certain lengths, a packing means positioned intermediate the limits of said measuring means for packing said material, a clamp member contracting means in connection with said packing means adapted 130

to receive a clamp member and contract the handle receiving portions thereof relatively to each other and clamp the clamp member about said material at its packed portion, a foot lever for shifting said packing means, and a hand operated cam means in connection with said packing means for actuating said clamp member contracting means.

3. In a machine of the class described, a frame, a pair of relatively contractible jaws supported by said frame and adapted to receive a yarn clamp member therebetween, means for relatively contracting said jaws, and a shiftable yarn packing member mounted on said frame in operative relation with said means for actuating said means and said jaws.

4. In a machine of the class described, a frame, a pair of relatively contractible jaws supported by said frame and adapted to receive a yarn clamp member therebetween, means for relatively contracting said jaws, means for normally holding said jaws in a separated position, and a bifurcated yarn packing arm pivotally mounted on said frame and adapted to straddle said jaws and to actuate said jaw contracting means.

5. In a machine of the class described, a frame, a pair of relatively contractible jaws supported by said frame and adapted to receive a yarn clamp member therebetween, means for relatively contracting said jaws, means for normally holding said jaws in a separated position, a bifurcated yarn packing arm pivotally mounted on said frame and adapted to straddle said jaws and to actuate said jaw contracting means, a foot operated means for shifting said packing arm, and a lever actuated cam means for shifting said packing arm beyond its normal packing position whereby said jaw contracting means is actuated.

6. In a machine of the class described, a frame, a pair of pivotally mounted, mutually contractible, yarn clamp member contracting arms, and a rack and gear means for rotating said arms about their pivotal mountings.

7. In a machine of the class described, a frame, a pair of pivotally mounted, mutually contractible, yarn clamp member contracting arms, a rack and gear means for rotating said arms about their pivotal mountings, a bifurcated yarn packing arm pivotally mounted on said frame and adapted to straddle said yarn clamp member contracting arms, and lever and link means for actuating said packing arm and said yarn clamp member contracting arms.

8. In a machine of the class described, a frame, a pair of pivotally mounted yarn clamp member contracting arms, a rack and gear means for rotating said arms about their pivotal mountings, means for holding said arms in a normally open position, a bi-

furcated yarn packing arm pivotally mounted on said frame and adapted to straddle said yarn clamp member contracting arms, a foot lever and link means pivotally connected to said packing arm, a cam member 70 rotatably mounted on said frame, and a hand lever connected to said cam member, said cam member being adapted to engage an extended portion of said packing arm when said foot lever is shifted, for forcing 75 said packing arm beyond its normal packing position and actuating said rack and gear means.

9. In a machine of the class described, a frame, a pair of spaced apart housings, a pair of relatively contractible arms pivotally mounted within said housings and provided with teeth at their one ends, each of said arms being formed on one side to conform with the shape of and receive a clamp member, and a gear rack reciprocally mounted between said arms in engagement with the teeth thereof.

10. In a machine of the class described, a frame, a pair of spaced apart housings, a pair of relatively contractible arms pivotally mounted within said housings and provided with teeth at their one ends, each of said arms being formed on one side to conform with the shape of and receive a clamp member, a gear rack reciprocally mounted between said arms in engagement with the teeth thereof, and a detachable shoe mounted at the end of said rack adjacent the clamp receiving portion of said arms and adapted to receive the band portion of a clamp member.

11. In a machine of the class described, a frame, a pair of spaced apart housings, a pair of relatively contractible arms pivotally mounted within said housings and provided with teeth at their one ends, each of said arms being formed on one side to conform with the shape of and receive a yarn clamp member, a gear rack reciprocally mounted between said arms in engagement with the teeth thereof, said gear rack having laterally extended portions, a packing arm pivotally mounted on said frame and provided with spaced apart packing portions adapted to straddle said housings and said spaced apart packing portions being provided at their one and coincident sides with bifurcated portions adapted to straddle the yarn, adapted to be positioned in the yarn clamp member between said housings, the latter portions of said packing arm being adapted to engage the laterally extended portions of said rack and means for actuating said packing arm.

12. In a machine of the class described, a frame, a pair of spaced apart housings, a pair of relatively contractible arms pivotally mounted within said housings and provided with teeth at their one ends, each of

said arms being formed on one side to conform with the shape of and receive a yarn clamp member, a gear rack reciprocally mounted between said arms in engagement 5 with the teeth thereof, said gear rack having laterally extended portions, a packing arm pivotally mounted on said frame and provided with spaced apart packing portions adapted to straddle said housings and said 10 spaced apart packing portions being provided at their one and coincident sides with bifurcated portions adapted to straddle the yarn, adapted to be positioned in the yarn clamp member between said housings, the 15 latter portions of said packing arm being adapted to engage the laterally extended portions of said rack, said packing arm being provided with an extended portion having a revoluble roller, a foot operated lever 20 connected with said packing arm, and a

pivots mounted hand operated lever provided with a cam member, said cam member being adapted to engage said roller when said foot operated lever is depressed.

13. In a mop assembling machine, a measuring means, a yarn cutting means in connection with the said measuring means for cutting the yarn to certain lengths, a packing means positioned intermediate the limits of said measuring means for packing said 25 yarn, and a clamp member contracting means in connection with said packing means adapted to receive a clamp member and contract the same around the packed portion of said yarn.

In testimony whereof, we have hereunto set our hands at San Diego, California, this 12th day of September, 1924.

JOB C. HUGULEY.
CARL M. HUGULEY.
